UNITED STATES PATENT OFFICE.

JOHN H. BROWN, OF READING, PENNSYLVANIA.

TUBULAR STRUCTURE.

SPECIFICATION forming part of Letters Patent No. 630,585, dated August 8, 1899.

Application filed November 12, 1898. Serial No. 696,215. (No model.)

To all whom it may concern:

Be it known that I, JOHN H. BROWN, a citizen of the United States, and a resident of Reading, in the county of Berks and State of Pennsylvania, have invented a new and useful Improvement in Tubular Structures, of which the following is a specification.

My invention relates to an improvement in tubular structures in which the wall of the structure is formed by overlapping curved sections.

A practical embodiment of my invention is represented in the accompanying drawings, in which—

15 Fig. 1 is a view of a tubular structure in end elevation, showing in connection therewith an inner lining-tube, a surrounding wire jacket, and an exterior tubular jacket. Fig. 2 represents in end elevation a tubular structure composed of a less number of overlapping sections than the structure shown in Fig. 1. Fig. 3 is a view in end and side elevation of a blank from which one of the sections of a cylindrical tubular structure is formed. 20 Fig. 4 is a similar view showing the section bent into the shape which it assumes when the sections are assembled. Fig. 5 represents in end and side elevation a blank from which a tapered section is formed. Fig. 6 is a 25 similar view showing the tapered section curved in the form which it assumes when the sections are assembled, and Fig. 7 is a view of a tapered lining-tube.

The several sections which enter into and 35 compose the body of the tubular structure are of involute or convolute shape in cross-section and the number of sections may be two or more, as found most expedient. When 40 assembled to form the tubular structure, each of the involute or convolute sections is arranged to begin at a point distant from the beginning of the preceding section, the distance of the two points of beginning from one another, measured along the circumference 45 of the circumscribing circle, being such a part of the entire circumference as one is of the number of sections used. For example, if two sections are used then the distance between the two points of beginning will be one-half the circumference of the circumscribing circle. If three sections are used, the distance 50 between the points of beginning of each two

consecutive sections will be one-third of the circumference of the circumscribing circle, and so on.

In using the term "circumscribing circle" I refer to a circle which is drawn with a radius equal to the distance between the outermost point of the convolute or involute curve and the center from which the convolute is generated. Furthermore, in the manufacture of a tubular structure from sections so curved the thickness of the several curved sections is a matter to be considered in its relation to the number of sections employed in order to maintain a wall of equal thickness in the completed structure. This thickness may be determined by dividing the distance between the outermost point of the convolute and the innermost point of the convolute curve, measured on a radial line of the circumscribing circle, into a number of equal parts corresponding to the number of sections to be employed. For example, if two sections are to be employed then the thickness of the section should be one-half of the distance between the outermost and innermost points of the convolute curve measure, as above stated. If three sections are to be employed, each should be one-third of such distance, and so on.

In the form shown in Fig. 1 twenty convolute sections are employed in the body of the tubular structure, and in the form shown in Fig. 2 four sections are employed.

For purposes of convenience my present invention will be explained by reference to the structure shown in Fig. 2. The several convolute sections there shown are represented by A A' A'' A''. The circumference of the circle is denoted by B, its center by b, and the radial line for determining the thickness of the respective sections by b'. In this instance each section has a thickness equal to one-quarter of the distance between the points C C' measured on the radial line b'. Furthermore, the points of beginning of each of these involute sections will be one-quarter the length of the circumference B of the circle, as shown by the radial lines extended from the center b to points exterior to the circumference of the circle.

In practice I have found it desirable to form the several involute or convolute sec-

tions of sheet metal—such, for example, as sheet-steel—which may be first formed in a flat blank, as shown in Fig. 3, and then bent into the involute or convolute form shown in Fig. 4. When the number of sections to enter the particular structure to be made have thus been similarly formed, they may be slid into position endwise after the manner of telescoping, and when so arranged they will become completely interlocked so far as internal pressure in a radial direction is concerned, and the tubular structure so formed may be put to practical use, either with or without additional interior and exterior tubes or jackets, as may be desired.

When a tapered structure is required, the tapered blank shown in Fig. 5 is preferably used, and the convolute section becomes gradually smaller as it approaches the taper end of the curved blank.

For the purpose of leaving the interior of the tubular structure smooth I bevel the inner edges of the several sections, cutting them away either before or after assembling along the dotted line D, (shown in Fig. 2,) and for the purpose of making the exterior of the structure smooth and free from shoulders I may bevel the outer edges of the several sections along the dotted line D' of Fig. 2. When the tubular structure formed as above is to be utilized as a gun, I find it desirable to insert a lining-tube E, as shown in Fig. 1, and to wind the exterior with the wire F under suitable tension and protect the wire throughout a portion of or the entire length of the structure by an exterior tubular jacket G.

The tapered involute structure has its advantages in that it can easily be constructed of any desired length with a true internal taper admitting of the introduction of a lining-tube H, having its exterior tapered to correspond to the interior taper of the sectional structure, and when introduced the tapered lining-tube will have a tendency to drive the adjacent faces of the curved sections into ex-

tremely close contact and will have the further advantage of being easily removed the moment it is driven endwise a slight distance to release it.

It is obvious that changes in the form and arrangement of the sections might be resorted to without departing from the spirit and scope of my invention. Hence I do not wish to limit myself strictly to the structure herein set forth; but

What I claim is—

1. A tubular structure composed of involute or convolute sections arranged to overlap one another at intervals, substantially as set forth.

2. A tubular structure composed of involute or convolute sections arranged to overlap one another at intervals and having their interior and exterior exposed edges beveled, substantially as set forth.

3. A tubular structure of tapered form composed of involute or convolute sections arranged to overlap one another at intervals, substantially as set forth.

4. A tapered tubular structure composed of overlapping convolute sections in combination with a lining-tube having its exterior wall tapered, substantially as set forth.

5. A tubular structure composed of overlapping involute or convolute sections and an exterior jacket of wire, substantially as set forth.

6. A tubular structure composed of overlapping involute or convolute sections in combination with an inner lining-tube and an exterior jacket of wire, substantially as set forth.

In testimony that I claim the foregoing as my invention I have signed my name, in presence of two witnesses, this 1st day of September, 1898.

JOHN H. BROWN.
